UNITED STATES PATENT OFFICE.

HOLLIS BRANSCOMB LONG, OF NASHVILLE, TENNESSEE.

SPRINKLER-HEAD.

1,306,490.

Specification of Letters Patent. Patented June 10, 1919.

Application filed March 26, 1919. Serial No. 285,267.

To all whom it may concern:

Be it known that I, HOLLIS BRANSCOMB LONG, a citizen of the United States, and a resident of Nashville, in the county of Davidson and State of Tennessee, have invented certain new and useful Improvements in Sprinkler-Heads, of which the following is a specification.

My present invention relates generally to 10 sprinkler heads and more particularly to fire extinguishing apparatus, my object being the provision of a sprinkler head embodying a novel construction whereby to increase its effectiveness and avoid all danger of its 15 failure in action.

My invention especially resides in the connections or struts utilized between the clamping means and the pipe closing cap of a 20 sprinkler head, and my invention aims not only at a novel construction of such connections or struts, but also has for its object the provision of a novel arrangement whereby two struts may be effectively utilized in connection with each sprinkler head for release 25 of the pipe closing cap upon failure or collapse of either of the struts.

In the accompanying drawings which illustrate my present invention,

Figure 1 is a side elevation of the 30 sprinkler head complete,

Fig. 2 is a detail perspective view of one part of one of the struts,

Fig. 3 is a similar view of the other part of one of the struts, and

Fig. 4 is a top plan view of the pipe closing cap removed.

Referring now to these figures, my invention is applied to a sprinkler head for fire extinguishing apparatus including a frame 10 which carries a threaded pipe-engaging extension 11, the upper open end of which extension 11 is normally closed by a cap 12, which fits and is held thereon, either with or without a suitable gasket 13 as may be 15 needed. At its upper portion, the frame 10 has an internally threaded bearing 14 whose axis is alined with that of the extension 11, for the reception of a pressure screw 15 which, as usual, supports an upper deflector 20.

The closing cap 12, as particularly seen in Fig. 4, is provided with a pair of bearing recesses 17 adjacent to one another, for the reception of the lower ends of the two 25 struts, generally seen at 18 in Fig. 1, in connected operative relation, each of these struts

including plates 19 and 20, and the plates 19 having lower rounded end portions which seat in the bearing grooves 17 of the cap 12.

By reference to Fig. 1 it will be noted 60 that each of the struts 18 is disposed at an angle, the two struts diverging in an upward direction away from the closing cap 12, with their upper ends disposed for engagement by the bridge piece 21 at points adjacent the opposite ends of the said bridge piece, which latter is engaged at its center by the lower end of the pressure screw 15 so as to thus force the cap into tightly closed position and hold the same until one or the 70 other of the struts collapse. At this point it should be particularly noted that in view of the particular disposition of these struts, collapse of either one of the pair of struts instantly releases the several parts and the 75 cap 12 is forced by the water pressure off of its seat, bringing the stream of water for upward movement against the distributor 16.

As above stated, the lower end 20 of the 80 part 19 of each strut engages the closing cap 12, and likewise the upper rounded end 22 of the part 20 has bearing connection with its respective end of the bridge piece 21, the inner portion of the two parts 19 and 20 85 of each strut overlapping one another in mutually bearing relation by virtue of the offset 23 of the part 20 adjacent its outer end, beneath which it has a rounded bearing 24 for the upper end 25 of the part 19. The 90 part 19 is furthermore provided with a bracket 26 adjacent to which the inner free end 27, with its knife edge as seen in Fig. 3, extends, this bracket forming a support for the fusible solder 28 which thus normally 95 extends around the inner end 27 of the part 20 and holds the parts in their mutually bearing relation above stated.

Thus in action it is obvious that the two struts 18 disposed and clamped as seen in 100 Fig. 1, will serve to effectively hold the closing cap 12 in non-leaking relation upon the upper end of the pipe-engaging extension 11 of the sprinkler head, and it is equally obvious that the parts will be instantly released for action in use, upon the failure or collapse of either of these struts, the action taking place upon the collapse of one or the other of the struts whose fusible solder 28 melts away sufficiently to release the inner 110 end 27 of its upper part 20.

Thus I avoid in a great measure the

danger of relying upon a single fusible joint, deterioration of which may cause hardening of the material after long inaction, and prevent its ready response to surrounding heat, and it is to be observed that I accomplish the advantages stated with a simple inexpensive arrangement of a strong and durable nature.

I claim:—

- 5 1. In a sprinkler head, a frame, a pipe closing cap, struts having bearing at one end on said cap and diverging from the cap, each of said struts including two parts having bearing on one another, fusible solder normally connecting the parts of each of the struts, a bridge piece, the extremities of which engage the opposite ends of said struts, and a pressure screw having a threaded bearing in the frame and engaging said bridge piece at its center.
- 10 2. In a sprinkler head, a frame, a pipe closing cap, struts having bearing at one end on said cap and diverging from the cap, each of said struts including two parts having bearing upon one another and provided with a fusible connection, a bridge piece engaging the struts at opposite ends, and a pressure screw having a threaded bearing in the frame and engaging the said bridge piece at a point between the adjacent ends of the struts.
- 15 3. In a sprinkler head, a frame, a pipe

closing cap having bearing grooves in its surface adjacent to one another, struts having bearing at one end in the grooves of the closing cap and each including two fusibly connected parts lapping and having bearing on one another, the opposite ends of the said struts being spaced apart, and a bridge piece engaging the last mentioned ends of the struts, and a pressure screw having a threaded bearing in the frame and engaging the said bridge piece at a point between the adjacent ends of the struts.

4. In a sprinkler head, a frame, a pipe closing cap therein, a pressure screw having a threaded bearing in the frame, a bridge piece engaged by the pressure screw, and struts disposed between the bridge piece and the said closing cap, and having bearings at their opposite ends in connection therewith, each of said struts including two lapping parts, having their outer ends free, one of said parts being provided with an offset bearing adjacent its free outer end, for the reception of the inner end of the other part, and fusible solder normally connecting the inner lapping portions of the parts of each strut, as described.
